US00D862778S

(12) **United States Design Patent** (10) Patent No.: **US D862,778 S**
Antony et al. (45) Date of Patent: ** Oct. 8, 2019

(54) LIGHTING MODULE LENS	2,715,449 A	8/1955	Lemmerman et al.
(71) Applicant: Flex Ltd. , Singapore (SG)	D188,436 S	7/1960	Budke et al.
	3,009,055 A	11/1961	Franzese
	3,209,142 A	9/1965	Michel et al.
(72) Inventors: Ashish Antony , Anna, TX (US); Jordon Musser , Dallas, TX (US)	D208,491 S	9/1967	Brooks
	D255,851 S	7/1980	Crane
	D291,598 S	8/1987	Elkerbout
	4,726,781 A	2/1988	Bemhart et al.
(73) Assignee: FLEX LTD , Singapore (SG)	6,061,978 A	5/2000	Dinwoodie et al.
	6,076,943 A	6/2000	Lassovsky
(**) Term: 15 Years	6,274,402 B1	8/2001	Verlinden et al.
(21) Appl. No.: 29/614,664	6,295,818 B1	10/2001	Ansley et al.
(22) Filed: Aug. 22, 2017	6,313,395 B1	11/2001	Crane et al.
(51) LOC (12) Cl. 26-99	6,333,457 B1	12/2001	Mulligan et al.
(52) U.S. Cl. D26/118	6,337,283 B1	1/2002	Verlinden et al.
(58) Field of Classification Search	6,387,726 B1	5/2002	Verlinden et al.
